UNITED STATES PATENT OFFICE

2,028,353

FRAME CORNER STRUCTURE

William Francis Roberts, Baltimore, Md., assignor
of one-half to Charles J. Seebach, Baltimore,
Md.

Application April 8, 1935, Serial No. 15,335

1 Claim. (Cl. 156—14)

This invention relates to screen-frames, and especially to an improved frame corner structure, also to an article of manufacture and merchandise which constitutes an improved frame-corner-member.

One object of this invention is to provide an improved frame corner structure that is exceedingly strong, rigid and secure, and which can be produced and applied at slight expense.

Another object is to provide an improved and exceedingly strong and rigid frame-corner-member by forming the same from a blank of sheet metal, or from other rigid sheet material, by pressing the blank into the shape of a channel-member whose channel-bottom is formed of parts that are substantially in angular relation to one another and which is continuous throughout its longitudinal and lateral extent, so that its rigidity is at the maximum for the required thinness of the sheet material.

Another object is to provide an improved knock-down frame structure which includes vertical and horizontal strips each having one end mortised and its other end square-cut, so the length can be reduced by merely square-cutting the originally square-cut end, thereby leaving the corner-joints of the frame unchanged in the operation of reducing the dimensions of the frame; also to supply the knock-down frame with the above-described frame-corner-members which will fit the adjoining ends of the frame-strips at whatever length they may be originally or after being square-cut.

Other objects and important features are pointed out or implied in the following detailed description, in connection with the accompanying drawing in which:

Fig. 1 is a perspective view of a frame-corner constructed and assembled according to this invention.

Fig. 2 is a bracketed view showing in perspective and in full lines the correlated ends of a vertical frame-strip and a horizontal frame-strip separated, and the broken lines showing the vertical frame-strip's normal position with respect to the horizontal frame-strip, a fragment of the cover-strip for a screen-edge being shown in a dropped position.

Fig. 3 is a perspective view of the frame-corner-member that comprises part of the assembly in Fig. 1.

Fig. 4 is a bottom plan view of the member shown in Fig. 3.

Fig. 5 is a longitudinal vertical sectional view

showing a modified form of the member shown in Fig. 3.

Fig. 6 is a cross sectional view along the line 6—6 of Fig. 5.

Referring to the drawing in detail wherein similar reference numerals refer to similar parts in the several views, the invention is described in detail as follows:

The three essential parts of my frame corner structure are shown assembled, in Fig. 1, in their normal relation, the horizontal frame-strip's square-cut end portion being indicated at 10, the greater part of this strip (including its mortised end) being omitted as if cut off at the end of the corner-securing member 11 which is here shown in its entirety; and the upper end-portion of the vertical frame-strip 12 having its mortise hidden by the adjoining square-cut end of the horizontal frame-strip; but, in Fig. 2, the mortise is defined by a vertical wall or surface 13 and a seat or surface 14, and will be referred to hereinafter as a one-angle mortise or uni-angle mortise. The vertical depth of this mortise is equal to the width or vertical measurement of the horizontal frame-strip 10, so the upper end of the vertical strip is flush or level with the upper surface of the horizontal frame-strip while the lower surface of the latter rests in its normal position on the seat or surface 14 and the square-cut end surface of the strip 10 fits snugly against the vertical surface 13.

Each strip 10 and 12 has its opposite vertical sides formed with grooves or kerfs 15. The frame-corner-member 11 is formed of a substantially quadrangular blank of rigid sheet material, preferably ductile sheet iron, steel, brass or aluminum, pressed into the shape shown, viz., into the channel-shape where the sides or walls are shown at 16 and 17 (in Figs. 1 and 2) and at 17a (in Fig. 5). Each side or wall is formed with two securing flanges 18 turned laterally at right angles to the major part of the wall and extending at right angles to one another. From another aspect, there are two pairs of securing flanges, those of each pair being parallel and extending inward towards one another; and although they are shown in spaced relation to one another (in Figs. 1 and 3), to provide an opening or clear space 19, they may be adjoined and united for providing greater rigidity, and an opening 19a may be provided in lieu of the opening 19, or the openings 19 and 19a may both be omitted in view of the fact that the sheet-material is ductile and soft and thin so that a sharp-pointed nail or tack can be driven through the walls at any chosen

point. However, the walls and their flanges must have considerable rigidity, so it is quite within the scope of this invention to make the flanges double-thick by turning the edges of the blank 5 upon the adjoining edge-portions before forming the blank into channel-shape. Moreover, the walls 16 and 17 may be stiffened, as are the walls 17a, by elongated bosses or ribs such as shown at 17b and/or 17c, or of any desired shape and 10 locality on the respective walls; but when the walls are of relatively thick and rigid material pressed or die-cast into shape, the bosses may be omitted, and any desired number of nailing openings may be provided through the walls, so 15 nails may be passed therethrough when securing a screen-fabric and edge-protecting strip 20 (Fig. 2) in place.

A very important feature of this invention resides in the lateral and longitudinal continuity 20 of the channel-bottom 21—22—23 (Figs. 1, 3 and 4) or 21a—22a—23a (Figs. 5 and 6), where it is seen that a substantially horizontal section 21 or 21a merges with a substantially oblique section 22 or 22a that merges with a substantially vertical section 23 or 23a; the unity and continuity 25 of these three sections making the channel bottom far more rigid than it would be if these three sections were in the same plane, or if any one of these parts or sections were not continuous 30 laterally or from wall 16 to wall 17 or 17a to 17a. It is quite within the scope of this invention to form the part 22 arcuate, as indicated by the

arcuate broken line in Fig. 3; also to form the member 11 or 11a from two blanks in such manner that they can be joined to one another by riveting, soldering, welding or otherwise securing them together at any appropriate part of the 5 channel-bottom 21—22—23 or 21a—22a—23a.

While describing my invention specifically, it is not my intention to limit my patent protection to these specific and precise details, for the invention is susceptible of numerous changes within the scope of the inventive ideas as implied and claimed.

What I claim as my invention is:

An article of manufacture and merchandise comprising a frame-corner-member of rigid sheet 15 material constituting a channel-member having walls each including two securing-flanges disposed longitudinally at right angles to one another, each flange of one channel-wall being laterally disposed at right angles to the main part 20 of this wall and projecting towards a similarly formed and arranged flange of the opposite channel-wall, said walls being connected by a channel-bottom which is laterally and longitudinally continuous and includes end portions substantial- 25 ly at right angles to one another and united with an intermediate portion that is substantially oblique to said end portions, whereby said walls are held in the maximum rigidity and stability with respect to one another. 30

WILLIAM FRANCIS ROBERTS.
